UNITED STATES PATENT OFFICE.

GOMER W. PRICE AND CURT F. ZIMANSKY, OF SAN FRANCISCO, CALIFORNIA,
ASSIGNORS TO G. W. PRICE PUMP AND ENGINE COMPANY, OF SAN FRANCISCO, CALIFORNIA.

ANTISAND BEARING.

Application filed May 21, 1921, Serial No. 471,456. Renewed March 17, 1923.

To all whom it may concern:

Be it known that we, GOMER W. PRICE and CURT F. ZIMANSKY, citizens of the United States, residing in the city and county of San Francisco and State of California, have invented a new and useful Improvement in an Antisand Bearing, of which the following is a specification.

Our invention relates to improvements in shaft bearings for rotary well pumps and the like wherein means are provided for preventing the entrance of sand into the bearing.

The primary object of our invention is to provide an improved pump shaft bearing.

Another object is to reduce wear on a pump shaft by preventing the entrance of sand from water pumped into the shaft bearings within the pump.

A further object is to circulate water around a pump shaft bearing to carry sand suspended in the water away from the bearing.

We accomplish these and other objects by means of the device disclosed in the drawings forming a part of the present specification wherein like characters of reference are used to designate similar parts throughout said specification and drawings and in which:

Figs. 1 and 1^a are broken side elevations of a well pump and casings, parts being broken away and shown in section to disclose the application of our improved shaft bearing.

Fig. 2 is a broken vertical section of the pump on a larger scale disclosing our invention applied thereto.

Fig. 3 is a view similar to Fig. 2 disclosing the application of our improved bearing to a pump having a runner of another type.

Referring to the drawings the numeral 1 is used to designate in general a well pump of the rotary type suspended in a well casing 2 by a pump casing 3 and driven by a drive shaft 4 extending from the pump to the surface of the ground through a shaft casing 6. Bearings 7 are provided at intervals in the shaft casing 6 to prevent whipping of the shaft 4. The pump and shaft casings and bearings 7 are fully described in a copending application, Serial

Number 471,460, May 21, 1921 and form 55 no part of the present invention. The shaft 4 is provided at the top thereof with a pulley 8 arranged to be driven from any suitable source of power in the usual manner.

The pump 1 comprises a plurality of bowls 11 having an inner wall 12 and an outer wall 14 connected in spaced relation by vertically disposed connecting webs 16 forming water passages 17 therebetween. 65 Runners or impellers 18 are mounted upon the shaft 4 within the bowls 11, said runners 18 having webs or vanes 19 adapted to force water upwardly into the water passages 17 when the shaft 4 is rotated. Bearings 21 are provided in the bowls 11 to receive the shaft 4 and hold the same in alignment.

In the present state of the art the bearings are cast as an integral part of the bowl, the bearing being connected with an inwardly projecting continuation of the upper portion of the inner wall of the bowl, the lower portion of the bearing being connected to the lower portion of the inner wall by a 80 continuous web. The water within the well usually carries sand and sediment in a suspended condition due to the operation of the runners in agitating and elevating the water. As the water passes upwardly from the lowermost bowls of the pump to receive further upward impetus from the rotating vanes of the next runner above an eddy due to the change in direction of flow of water is caused adjacent the upper end of the 85 bearing, within the reduced pressure area at the central portion of the runner. The reduced pressure adjacent the bearing and the eddy current formed therein co-act to cause sand and sediment carried by the passing water to be collected upon the uppermost end of the bearing, the continuous rotation of the shaft causing a portion of such sand and sediment to enter the bearing with obvious damage by abrasion to 90 both the shaft and the bearing.

To prevent sand and sediment from working into the bearing 21 we have provided a bearing formed separately from the bowl. The bearing 21 is provided with an annular 105 flange 24 adjacent the lower end of said bearing arranged to be engaged by and suitably secured to a shoulder 26 formed upon

the lower end of the inner wall 12 of the bowl. The upper portion 22 of the wall 12 is bored larger than the diameter of the shaft 4 above the bearing 21 as best disclosed in Figs. 2 and 3 of the drawings, a chamber 27 being formed by the wall 12 and the flange 24 to enclose the bearing 21. The flange 24 is provided with a plurality of outlet apertures 28 adjacent the bearing 21. The runners 18 are mounted immediately below the bearing 21 so that the vanes 19 will operate in the portion of the bowl 11 immediately below the flange 24. Rotation of the runners 18 causes a reduced pressure area to be formed at the inner end of the vanes 19, this reduced pressure creating a suction operating to draw water to replace that displaced from in front of the vanes 19, this suction operating to draw water from the chamber 27 through the apertures 28. In this manner a downward circulation of water is caused in the chamber 27 and all sand and sediment working into the upper end 22 of the wall 12 is carried past the top of the bearing 21 and discharged through the apertures 28 thereby keeping the bearing free from foreign material carried in the water. The portion 22 of the wall 12 is made to allow sufficient clearance for the shaft 4 to permit free passage of sand and sediment therethrough and into the chamber 27 without damaging the shaft by abrasion.

An annular flange 30, having the outer portion thereof downwardly inclined, is mounted upon the shaft 4 immediately above the bearing 21 to further deflect sand and sediment away from the bearing and into the chamber 27, thereby assisting the circulation above described in preventing the entrance of such sand into the bearing.

The sand discharged from the apertures 28 passes back into the pump through apertures 31 provided in the flanged type of runner 18 disclosed in Fig. 2. When a runner 18 of the type disclosed in Fig. 3 of the drawings is used no aperture 31 is necessary as the sand works out through the clearance at the outer rim of the runner.

Having thus described our invention that we claim as new and desire to secure by Letters Patent is:

1. The combination with a rotary well pump provided with bowls having water passages, a shaft and runners mounted therein, of a bearing mounted within each bowl to receive said shaft; and a suction chamber enclosing said bearing and arranged to cause sand admitted into said chamber above said bearing to be drawn away from said bearing by suction created within the chamber when the runners are operated.

2. The combination with a rotary well pump provided with bowls having water passages, a shaft and runners mounted there-

in, of a bearing mounted within each bowl of the pump to receive said shaft; a chamber formed within each bowl to enclose the bearing therein, said chambers being provided with outlets adjacent the suction area of the runners for circulating water through said chamber and past the bearing to carry sand suspended in the water away from the bearing.

3. The combination with a rotary well pump provided with a plurality of bowls having water passages, a shaft and runners therein, of a bearing mounted within each bowl of the pump to receive the shaft; and a chamber formed within each bowl and enclosing said bearing and provided with an upper passage surrounding said shaft and outlet apertures in the bottom of said chamber communicating with the passages of the bowl whereby rotation of said runners will produce a suction and circulation through said chamber to carry water and suspended sand through said chamber and away from the bearing therein.

4. The combination with a rotary well pump provided with a plurality of bowls having water passages, a shaft and runners therein, of a bearing mounted within each bowl of the pump to receive said shaft; and a flange connecting said bearing with the bowl and forming a suction chamber with said bowl and surrounding said bearing, said chamber having connection with the water passages to produce a circulation within said chamber to prevent the passage of water and suspended sand through said bearing when the runners are rotated.

5. The combination with a rotary well pump provided with a plurality of bowls having water passages, a shaft and runners therein, of a bearing mounted within each bowl of the pump to receive the shaft; a chamber formed within each bowl and enclosing said bearing and provided with an upper passage surrounding said shaft and outlet apertures in the bottom of said chamber communicating with the passages of the bowl whereby rotation of said runners will produce a suction and circulation through said chamber to carry water and suspended sand through said chamber and away from the bearing therein; and an annular flange secured to the shaft between the bearing and said upper passage to deflect said suspended matter away from the bearing.

6. The combination with a rotary well pump provided with a plurality of bowls having water passages, a shaft and runners mounted therein, of a flanged bearing secured within each bowl of the pump to receive said shaft and to form a chamber with said bowl about said bearing, said chamber having openings at top and bottom thereof to permit a circulation of water therethrough due to the suction created by the pump

runners, the bottom openings being outlets positioned between the bearings and the outer wall of the chamber to circulate water past the bearing for carrying suspended sand away from the bearing.

7. The combination with a rotary well pump provided with a plurality of bowls having water passages, a shaft and runners mounted therein, of a flanged bearing secured within each bowl of the pump to receive said shaft and to form a chamber with said bowl about said bearing, said chamber having openings at top and bottom thereof to permit a circulation of
- 10

water therethrough due to the suction created by the pump runners, the bottom openings being outlets positioned between the bearings and the outer wall of the chamber to circulate water past the bearing for carrying suspended sand away from the bearing; and an annular flange secured to the shaft between the bearing and the upper opening into the chamber to deflect said suspended sand away from the bearing.

In witness whereof we have hereunto set our signatures.

GOMER W. PRICE.
CURT F. ZIMANSKY.
